UNITED STATES PATENT OFFICE.

CLINT HENRY HULING, OF EL PASO, TEXAS.

HAT SHAPE RETAINER AND LOSS PREVENTING DEVICE.

1,333,314.

Specification of Letters Patent.

Patented Mar. 9, 1920.

Application filed April 22, 1919. Serial No. 291,897.

To all whom it may concern:

Be it known that I, CLINT H. HULING, a citizen of the United States, residing at El Paso, in the county of El Paso and State of Texas, have invented certain new and useful Improvements in Hat Shape Retainers and Loss Preventing Devices, of which the following is a specification.

My invention relates to new and useful improvements in hat shape retainers and loss preventing device combined, and consists generally of means applied to the sweat band of a hat, one portion of which engages the wearer's head to retain the hat thereon, while the other portion thereof is secured to the sweat band and retains the crown of the hat in its proper shape.

Another object of my invention resides in the provision of means which may be detached from the sweat band of a hat and folded into a comparatively small space whereby the device may be readily accommodated in a wearer's pocket.

Another object of my invention resides in the provision of a yieldable element which is stretched across the sweat band of a hat to form a chord, which will snugly engage the forehead of the wearer and thereby aid in retaining a hat upon the wearer's head.

A further object of the invention resides in the provision of a device of the above mentioned character including a yieldable element which may be easily and quickly detached or attached to the hat shape retainer which is secured to the sweat band.

Other objects and advantages of the invention will become apparent during the course of the following description.

40 In the accompanying drawings wherein like numerals are employed to designate like parts through the same,

Figure 1 is a vertical section taken through the hat showing a front elevation of my invention and applied to the front of a sweat band.

Fig. 2 is a bottom plan of the same.

Fig. 3 is an enlarged detailed perspective view of one end of the invention.

50 Fig. 4 is a perspective view of the hat shape retaining portion of my invention in a folded position.

Fig. 5 is a longitudinal section taken through the means for hinging together the 55 section of the hat shape retaining device, and

Fig. 6 is a transverse section through a portion of a hat illustrating the manner of attaching the invention to the sweat band thereof.

60

In the drawings, wherein for the purpose of illustration is shown the preferred embodiment of my invention, the numeral 7 indicates a hat in general of any desired style or shape and is provided with the usual sweat band 8.

The strip 9 composed of three sections hingedly connected together by means of loops 10, is secured to the sweat band adjacent the upper edge thereof. Each section 70 is provided with a plurality of openings adjacent their longitudinal edges so that the sections composing the strip 9 may be rigidly secured to the sweat band by sewing the same thereto or in any other suitable 75 manner. The strip consists of a central section 11, to each end of which is pivoted an end section 12. The lower edge of each end section is provided with a depending leg 13. If desired, the strip 9 may be secured to the inside face of the sweat band 80 and slits provided in the band for the passage of the legs 13. It is also to be understood that the strip 9 consisting of the three sections may be formed from any suitable 85 material which will hold its shape and accordingly retain the crown of the hat in its proper shape.

A yieldable element 14 in the form of an elastic strip, has its opposite ends looped 90 as at 15, which loops are adapted to engage with the depending legs 13 of the strip 9. Therefore, it will be clearly evident that when the strip 9 is applied to a sweat band, the yieldable element 14 will be stretched 95 across said sweat band to form a chord.

In practice the strip 9 which is composed of a plurality of sections hingedly connected together is secured to the front of the sweat band adjacent the upper edge thereof, and 100 inasmuch as the sections are pivotally connected together, the strip 9 as a whole will conform to the shape of the hat or sweat band.

Inasmuch as the strip is formed of some 105 substantial material, it will at all times retain the hat in its proper shape even though the yieldable element 14 is under tension which would tend to draw the legs 13 together. The loops 15 of the yieldable element are then placed upon the legs 13 and the element forms a chord. When the 110

wearer places the hat containing the invention upon his head, the yieldable element 14 is moved or stretched toward the strip 9 so that the wearer's head may be accommodated 5 within the sweat band. The normal tendency of the element 14 is to recoil to its proper position to form a chord and through this action will exert a pressure upon the forehead of the wearer and thereby prevent 10 the hat from blowing off of the head. It will be at once recognized that this device could be applied to women's hats and thereby eliminate the necessity of using hat pins. Further, it will be clearly understood that 15 the strip 9 may be detached from the sweat band and the chord folded as shown in Fig. 4 of the drawings, so that the entire device may be placed in the wearer's pocket until such time as it becomes necessary for him 20 to apply the device on windy and like disagreeable days.

The foregoing description and the drawings have reference to what may be considered the preferred, or approved, form of 25 invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent, is:

1. The combination with a hat having a 30 sweat band, of a substantially rigid curved strip secured to the upper edge of said band, a depending leg formed upon said strip ad-

jacent each end thereof, and a yieldable element having its opposite ends secured to said legs adjacent the lower edge of the sweat 40 band whereby the yieldable element is stretched across said strip to form a chord for retaining said hat upon the wearer's head.

2. The combination with a hat having a 45 sweat band, of a curved strip detachably secured to said sweat band and made up of a plurality of sections pivotally connected, and a yieldable element connected to said strip whereby the element is stretched across 50 the sweat band to form a chord for the purpose set forth.

3. The combination with a hat having a 55 sweat band, of a curved strip detachably secured to said sweat band, a depending leg formed upon the strip adjacent each end thereof, and a yieldable element having its opposite ends looped and received upon said legs whereby the element is stretched across 60 the sweat band to form a chord for the purpose set forth.

4. A hat attachment comprising a sectional strip of curved plates adapted to be placed against the sweat band of a hat, certain of said plates having projections thereon, and a flexible forehead engaging member carried by said projections and stretched 65 across one end of the hat opening.

In testimony whereof I affix my signature in presence of two witnesses.

CLINT HENRY HULING.
